TAG AND MEANS THEREON FOR ATTACHING
THE SAME TO GARMENTS

Samuel Weiss, Brooklyn, N. Y.

Application November 8, 1938, Serial No. 239,477

2 Claims.

(Cl. 40—20)

My invention relates to tags and means thereon for attaching the same to garments; and it consists in the novel features which are herein-after described.

5 One of the objects of my invention is to produce a tag with a means thereon for securely attaching the same to a button on a garment.

Another object is to make the said tag attachable to a buttonhole of a garment.

10 A further object is to eliminate metal piercing tongues or pins from the said attaching means.

A still other object is to have the said tag readily detachable from a garment.

15 Another object is to have said tag and the said attaching means thereon simple, durable and inexpensive.

Other objects and advantages will hereinafter appear.

20 I attain these objects by the tags and means thereon for attaching the same to garments, three modifications of which are illustrated in the accompanying drawing, or by any mechanical equivalents or obvious modifications of the same.

25 In the drawing Fig. 1 is a front view in elevation of one form of my tag and attaching means thereon; Fig. 2 is a cross-section on the line 2—2 of Fig. 1; and Fig. 3 is a section on the line 3—3 of Fig. 1.

30 Fig. 4 is a front view in elevation of another form of my tag and attaching means thereon; Fig. 5 is a cross-section on the line 5—5 of Fig. 4; and Fig. 6 is a section on the line 6—6 of Fig. 4.

35 The thickness of the tag and attaching means thereon is shown as exaggerated in Fig. 6 of the drawing.

Similar numerals refer to similar parts throughout the several views.

40 In the form of my tag and attaching means thereon, which are shown in Figs. 1, 2 and 3, 11 designates a fabric tag which has therein a slot 12 which is shown as disposed longitudinally with relation to the tag, and 13 is a reinforcement, or patch, which is shown in Figs. 2 and 3 as made of rubber or some similar resilient and flexible material; but it may also be made of fabric, if desired.

45 The patch 13 has therein a slot 14 which is shown as disposed transversely to the tag 11; the slots 12 and 14 are shown in Fig. 1 as disposed substantially at right angles to each other; but they may also be inclined to each other, if desired.

50 The patch 13 may be secured to the tag 11 by means of staples 15 which are shown in Fig. 1, and are omitted in Figs. 2 and 3; but other means

for securing the patch 13 to the tag 11 may also be employed, if desired.

The slots 12 and 14 serve to pass therethrough a button of a garment to which the tag 11 is to be connected.

5 The position of the slots 12 and 14 transversely to each other is conducive to security of the said connection, even if the patch 13 be made of fabric; when made of rubber as shown, additional security is thereby provided.

10 In the form of my tag and attaching means thereon which are shown in Figs. 4, 5 and 6, the patch 23 has therein a slot 24 which is disposed parallel to the slot 12 in the tag 11; the patch 23 is made of rubber as shown in Figs. 5 and 6; and the resilience of the patch 23 serves to keep the tag 11 and the patch 23 securely connected to a button of a garment, which is passed through the slots 12 and 24 when the tag 11 is connected to the garment.

20 The sizes of the slots may be different than as shown and may vary to suit the sizes of buttons on the sundry garments to which the tags are connected.

25 Staples 15 are shown in Fig. 4 as employed for securing the patch 23 to the tag 11; the staples 15 are omitted in Figs. 5 and 6.

30 The patch 23 may be made of some resilient material other than rubber, if desired; and the slot 24 in the patch 23 may be shorter than the slot 12 in the tag 11 to which it is connected.

35 Other variations are possible and parts of my invention may be used without other parts.

I do not, therefore, restrict myself to the details as shown in the drawing.

40 I claim as my invention and desire to secure by Letters Patent:

1. A tag and a means thereon for attaching the same to a garment comprising a patch of resilient material secured to said tag, said patch and said tag having therein each a slot for passing therethrough a button of a garment, whereby to connect said tag to said garment, said slots being disposed substantially transversely to each other, the said disposition of said slots and the resilience of said patch serving to securely keep 45 said tag attached to said garment.

2. A tag and a means thereon for attaching the same to a garment comprising a patch secured to said tag, said patch and said tag having therein each a slot for passing therethrough a button of a garment, whereby to connect said tag to said garment, said slots being disposed substantially transversely to each other, the said disposition of the slots serving to securely keep 50 said tag attached to said garment.

SAMUEL WEISS.
